UNITED STATES PATENT OFFICE.

FRANCIS STANHOPE PIT-TAYLOR, OF BLACKPOOL, ENGLAND.

CONCERTINA KEYBOARD.

1,417,107.

Specification of Letters Patent. Patented May 23, 1922.

Application filed November 11, 1919. Serial No. 337,353.

To all whom it may concern:

Be it known that I, FRANCIS STANHOPE PIT-TAYLOR, bachelor of medicine and bachelor of surgery, general medical practitioner, a subject of King George V of Great Britain and Ireland and of the Dominions beyond the Seas and Emperor of India, residing at 106 Bloomfield Road, Blackpool, in the county of Lancaster, England, have invented new and useful Improvements in Concertina Keyboards of which the following is a specification.

This invention relates to the keyboards of concertinas which are particularly adapted to the hands, the one to the one hand, and the other to the other hand of the player, the keys of each keyboard being grouped in parallel rows having six keys in each one, the keys being numbered from the left edge of the keyboard. These parallel rows of keys are placed one above the other so as to form six lines of keys which are perpendicular to the straight line L, shown in Figure 6 joining the lower edge of the second and sixth keys of any row, and to that shown in Figure 5 joining the lower edge of the first and fifth keys of each row. The keys in each parallel row of both keyboards, as is shown in Figures 5 and 6, are also placed in two straight lines which meet to form an angle, the vertex of the angle pointing upwards being the fourth key on the left keyboard, and being the third key on the right keyboard; the diatonic notes progressing as they do in the pianoforte from left to right on the left side, and from right to left on the right side being sounded by the 2nd, 3rd, and 4th keys of every row on the left side, and by the 3rd, 4th, and 5th keys of every row on the right side, and by the 6th key of every alternate row on the left side, and by the 1st key of every alternate row on the right side; the chromatic notes not progressing as the black notes do in the pianoforte being sounded by the remaining keys; the notes of the same name being in the same position in every alternate row only differing to the extent of being in octaves of lower or higher pitch.

The present invention (Pitt-Taylor, British, No. 136,300, application date Dec. 20, 1918, accepted Dec. 18, 1919) is an improved construction of keyboards of the foregoing description in which the first and second keys

on the left side, and the fifth and sixth keys on the right side in each row are placed in a more advantageous position for the fingers which sound them, and the chromatics of one octave found in every pair of rows are placed so as to progress from left to right on the left side and from right to left on the right side from the lowest to the highest note as the black notes do in the pianoforte, so that the beginning of one chromatic scale is found in one row of every pair, to enable them to be sounded more easily in certain chords.

In order that my said invention may be easily and clearly understood the keyboards are illustrated in the accompanying drawings, Figures 1 to 6, which are drawn to a scale a little more than one and a half times the actual size, and show an instrument with 30 keys on the left hand side and 42 keys on the right hand side, or 72 altogether in Figures 1 and 2, whilst Figures 3 and 4 show an instrument with 36 keys on each side, Figure 3 having one row less than Figure 1, and Figure 4 one row more than Figure 2, but an instrument of lesser or greater compass can be constructed if desired upon the same contrivance. Figures 5 and 6 show an instrument having the same number of keys on each side as Figures 3 and 4 have which illustrate my former patent, Pitt-Taylor, British, No. 109,423 accepted Sept. 13, 1917.

Figures 1, 3, and 5 of the accompanying drawings show the keyboard on the right hand side of the concertina, whilst Figures 2, 4, and 6 show that on the left hand side of the instrument.

The compass shown in Figure 2 on the left hand side extends from C sharp on the second leger line below the line on the bass staff to G flat on the third line above the line of the same staff; or from C sharp in the second octave to G flat in the fourth octave of a piano commencing its compass with A in the first octave.

The compass shown in Figure 4 extends from G in the fourth space below the line on the bass staff to F sharp in the third space above the line of the same staff, or comparing with the piano keyboard from G in the first octave to F sharp in the fourth octave.

On the right hand side, Figure 1, the com-

100

105

pass extends from G in the third space below the line of the treble staff to C in the sixth space above the line of the same staff, or from G in the third octave to C in the

5 seventh octave.

The compass shown in Figure 3 extends from G in the third space below the line of the treble staff to F sharp in the fourth space above the line of the same staff, or

10 from G in the third octave to F sharp in the sixth octave. Figures 3 and 4 show certain lines and angles which are referred to in the detailed description. The keys of each row besides being labelled with reference to the

15 fingers are numbered on both sides from the left edge of the keyboard with the numbers I to VI placed above the finger labels. Thus, in Figure 1 can be seen seven different-number rows of six keys numbered I

20 to VI, and six same-number rows of seven keys each of which is the same numbered key of each of the different-number rows. In Figure 2 on the other hand, there are only five different-number rows of six keys,

25 and therefore six same-number rows of five keys. In Figures 3 and 4 there are six different-number rows as well as six same-number rows.

I will now consider in detail the characteristic features of the invention.

First, the two outermost keys of each row, in Figures 1, 2, 3 and 4, which have been named OLFK or outer little finger key, and LFK or little finger key on each side are placed lower in position so that together with the RFK or ring finger key they form three keys in a straight line marked ZZ in

35 Figures 3 and 4, which line drawn through the centres of these keys and prolonged is in a line with the middle of the space between the two MFK's or middle finger keys, namely, the one of the same row and the other of the row above, named 4B and 4F in

40 Figure 3, and 2B and 2F in Figure 4, and parallel with the three keys, the MFK of the same row, the IFK or index finger key of the row above, and the OIFK or outer index finger key of the second row above.

Second, the OIFK, the IFK, and the MFK on each side are in a straight line marked YY in Figures 3 and 4, which line drawn through the centres of these three keys and prolonged is in a line with the middle of the space between the two RFK's, namely, the

55 one of the same row, and the other of the row above, and parallel with the three keys the RFK of the same row, the LFK of the row above, and the OLFK of the second row above.

Third, the RFK and the MFK of each row on each side are in a straight line, marked TT in Figures 3 and 4, which line drawn through the centres of these two keys and prolonged on each side of them is in a line with the centres of the OLFK and the

60 OIFK of the row above, and passes through

the middle of the space between the two LFK's and the two IFK's, namely, the ones of the same row, and the others of the row above.

The keyboard on each side is thus divided 70 into two sets of 3 keys in straight lines, as indicated by lines YY and ZZ in Figures 3 and 4, and one set of two keys in a straight line with the first and sixth keys of the row above indicated by the line TT, which two 75

keys are the innermost ones of the two sets of three keys. This line passing through the two keys, the MFK and the RFK of one row, termed TT, forms with the line YY passing through the OIFK, IFK, and MFK 80

on each side an angle, whose vertex being upwards is at the MFK, and the line connecting the middle of the keys IFK and RFK will be found to touch the lower edge of the MFK, and to be horizontal. This 85

angle is the same as that described in my former patent Pitt-Taylor, British, No. 109,423, application date June 5, accepted Sept. 13, 1917, as is shown in Figures 5 and 6. The above line TT, also forms with the 90

line ZZ passing through the OLFK, LFK, and RFK on each side an angle, whose vertex being upwards is at the RFK, and the line connecting the middle of the keys LFK and MFK marked RR will be found if pro- 95

longed in one direction to touch the upper edge of the OLFK of the same row, and in the other direction to touch the lower edge of the IFK of the row above, and if pro- 100

longed still further to be midway between the two OIFK's, namely, those of the first and second rows above. It is this additional angle together with the changes re- 105

sulting therefrom, and the alteration in the order of the chromatic notes which distin- 110

guishes this keyboard from that described in my former patent Pitt-Taylor, British, No. 109,423 app. June 5, acc. Sept. 13, 1917, so that the chief characteristics of this key- 115

board are that the six keys in every row on both sides are placed in such a position that they form (1) two angles instead of the one shown in Figures 5 and 6, (2) two sets of three keys shown in Figures 1, 2, 3 and 4 instead of one series of three and another of 120

four keys shown in Figures 5 and 6, and (3) one set of two keys formed by one key of each of the above two sets, which set is in a straight line with the first and sixth keys of the row above, and represents all that is 125

left of the old series of four keys in a straight line shown in Figures 5 and 6 and illustrating my former patent mentioned aforesaid.

The advantage obtained by this alteration 125 is firstly, that it carries out the contrivance of having as many keys in series of three in a straight line as is possible more thoroughly than formerly, and moreover, by the keyboard being evenly divided up into two por- 130

tions, the previous irregularity is eliminated, so that the regularity and greater simplicity provided will afford very much better conditions for reaching the acme of technical perfection in playing the instrument, and secondly, it enables the little and ring fingers to play the duads G sharp D, G C sharp, GE and AD more easily than formerly.

Second, the three keys which sound sharps 10 in each row of keys which contain them on both sides, the order of which in my aforesaid patent shown in Figures 5 and 6 from left to right on the left side, and from right to left on the right side is D sharp, F sharp, 15 and C sharp is changed, so that the sharps are placed as the black notes are in the pianoforte, that is, in the order C sharp, D sharp, and F sharp, or G flat, as is seen in Figures 2, 3 and 4.

20 The bottom different-number row of Figure 2, the second different-number row from the bottom of Figure 1, and every alternate different-number row in both figures show that the above-named three chromatic notes 25 are sounded by the three keys named OLFK, IFK, and OIFK, whilst the bottom different-number row of Figure 1, the second different-number row from the bottom of Figure 2, and every alternate different-number 30 row in both figures show that the remaining chromatic notes G sharp and A sharp are sounded by the two keys named OLFK and IFK, or, in other words, the outermost three keys, one on one side and two on the other 35 side of one different-number row, and one outermost key on one side, and one key next to an outermost key on the other side of the other different-number row of every pair of such rows are chromatic sounders.

40 In this invention, then, is thus combined for the first time two contrivances (A) the one in which for anatomical and musical advantages the diatonic notes are sounded, the keys being numbered from the left edge of 45 the keyboard, by the 2nd, 3rd, and 4th keys of every row on the left side, and by the 3rd, 4th, and 5th keys of every row on the right side, and by the 6th key of every alternate row on the left side, and by the 1st 50 key of every alternate row on the right side, and in which chromatic notes are sounded by the remaining keys, and (B) the other, in which each key in any row is as far as possible an equal interval of pitch in either 55 a forward or backward direction apart from the same key in the row above or in the row below, and therefore possesses a musical availability which is to the greatest extent possible, the best for all scales alike. Contrivance (B) has been attained without contrivance (A) by causing the six keys of each row to sound the notes of half an octave of a regular chromatic scale so that every pair of rows sounds the notes of a complete octave 60 of a chromatic scale in my patent specifica- 65

tion Pitt-Taylor, British, No. 102,552 app. date Mar. 7, 1916, acc. Dec. 14, 1916. Contrivance (A) has been combined with an application of contrivance (B) to the diatonic notes only, which are arranged so that 70 they progress as they do in the pianoforte from left to right on the left side, and from right to left on the right side, whilst the chromatic notes are not placed like the black notes are in the pianoforte in my aforesaid 75 patent Pitt-Taylor, British, No. 109,423, app. date June 5, 1917, acc. Sept. 13, 1917, shown in Figures 5 and 6.

Contrivance (A) has been combined with the application of contrivance (B) to both 80 diatonic and chromatic notes in this invention by not only having the diatonic notes to progress as they do in the pianoforte, but by having the chromatic notes to progress like the black notes do in the pianoforte 85 though in a separate positional way from that of the diatonic notes which form with them the notes in a chromatic scale. In this pianoforte way both series of notes, diatonic and chromatic, advance in accordance with 90 their respective positions in each octave, from left to right on the left side, and from right to left on the right side. The chromatic notes are thus placed nearer to their respective diatonic notes than previously. 95 Since the essential element in contrivance (B) is the regular, as opposed to any irregular order of both diatonic and chromatic notes, and this regular order is separately reproduced in this invention, it logically 100 follows that the chromatic notes are placed as close to their position in a pianoforte chromatic scale as the separate position of both diatonic and chromatic notes due to contrivance (A) will permit. 105

By this alteration, moreover, certain scales, especially the major flat scales, certain common chords, such as, BDF sharp B, F sharp A C F sharp, C sharp E G C sharp, D sharp F sharp A D sharp, A sharp C sharp E A sharp; C E flat G C, etc., and chords of the dominant seventh, such as, G sharp BDF sharp, BD sharp F sharp A, D sharp F sharp A C, F sharp A sharp C sharp E, E flat G flat B flat D flat, and the like, are made easier 110 to play without at the same time making any other chords less easy to play, so that the common chord of a note, its third, fifth, and octave, and the dominant seventh chord of a note, its third, fifth, and seventh are now 115 found to be obtained without difficulty throughout all scales alike. 120

What I claim and desire to secure by Letters Patent of the United States of America is:—

1. A concertina having two chromatic keyboards, one keyboard particularly adapted to one hand, the other keyboard to the other hand of the player, having its keys grouped in parallel rows of six keys in each 130

one, the rows being placed one above the other so as to form six lines of keys which are perpendicular to the straight line connecting the upper edge of the second and 5 fourth, and passing through the middle of the third key, on the right side, numbering the keys from the left edge of the keyboard, and to the straight line connecting the upper edge of the third and fifth, and passing 10 through the middle of the fourth key on the left side; the keys of each row forming two angles; the outer arm of each angle being formed by three keys in a straight line; the vertices of the angles 15 pointing upwards being the third and fourth keys; one angle being higher than the other, and the slope of the outer arm of the higher angle being less than the slope of the outer arm of the lower angle substantially as de- 20 scribed.

2. A keyboard with the keys grouped in pairs of rows of six, the keys of every pair being able to sound when pressed the naturals and the chromatics of one octave, 25 those for the chromatic sounders being for one row the three outermost keys one on the one side and two on the other side of one row, and for the other row one outermost key on one side and one key next to an 30 outermost key on the other side of the other row sounding in the first row the notes C sharp, D sharp and F sharp, and in the other

row G sharp and A sharp: every alternate row having keys for chromatic sounders of the same name and in the same position that 35 only differ from each other by being in octaves of lower or higher pitch substantially as described.

3. A concertina having two chromatic keyboards, one for each hand of the player, the 40 keys of each keyboard grouped in pairs of rows of six, the keys of every pair being able to sound when pressed the naturals and the chromatics of one octave, those for the chromatic sounders being for one row the 45 three outermost keys one on the one side and two on the other side of one row, and for the other row one outermost key on one side and one key next to an outermost key on the other side of the other row sounding 50 in the first row the notes C sharp, D sharp and F sharp, and in the other row G sharp and A sharp; sounding in both cases these notes from left to right on the left side and from right to left on the right side: every 55 alternate row having keys for chromatic sounders of the same name and in the same position that only differ from each other by being in octaves of lower or higher pitch substantially as described.

Signed at 106, Bloomfield Road, Blackpool, in the county of Lancaster, England, this 25th day of October, 1919.

FRANCIS STANHOPE PITT-TAYLOR.
